UNITED STATES PATENT OFFICE

109,731

DESIGN FOR A TAX STAMP OR SIMILAR ARTICLE

Anthony Rabito, Elmhurst, N. Y., assignor to The State of California

Application October 16, 1937, Serial No. 72,220

Term of patent 3½ years

To all whom it may concern:

Be it known that I, Anthony Rabito, a citizen of the United States, residing in Elmhurst, in the county of Queens, in the State of New York, have invented a new, original, and ornamental Design for a Tax Stamp or Similar Article, of which the following is a specification, reference being had to the accompanying drawing, forming part thereof.

The figure is a plan view of a stamp showing my new design on an enlarged scale in the ratio of 3 to 1.

I claim:

The ornamental design for a tax stamp or similar article, substantially as shown and described.

ANTHONY RABITO.
